UNITED STATES PATENT OFFICE.

JOHN BEISWANGER, OF STEUBENVILLE, OHIO, ASSIGNOR TO GILL BROTHERS COMPANY,
OF STEUBENVILLE, OHIO, A CORPORATION OF WEST VIRGINIA.

DESIGN FOR A BAKING-DISH.

52,726.

Specification for Design.

Patented Dec. 10, 1918.

Application filed May 6, 1918. Serial No. 232,943. Term of patent 7 years.

To all whom it may concern:

Be it known that I, JOHN BEISWANGER, a citizen of the United States of America, and resident of Steubenville, county of Jefferson, State of Ohio, have invented a certain new, original, and ornamental Design for a Baking-Dish, of which the following is a specification.

In the accompanying drawing I have illustrated a baking-dish constructed in accordance with my invention.

Figure 1 is an elevation of the dish; and

Fig. 2 is a bottom plan.

The subject of the invention is a baking-dish of transparent material, oval in plan, and having shallow side walls 2, flaring slightly outward. The walls are ornamented as to their external surfaces with Doric flutes shading at their upper edges into the smooth surface 3 of the top edge of the dish

and at their bottom ends joining the smooth surface 4 which encircles the bottom edge of the side walls, or the periphery of the bottom of the dish.

The outer surface of the bottom of the dish is ornamented with radial flutes 5 joining the peripheral plain surface 4.

The whole constitutes an oval baking-dish with vertically fluted sides and radially fluted bottom.

Having thus described and illustrated my invention, I claim:

The ornamental design for a baking-dish, substantially as shown and described.

Signed by me at Steubenville, Jefferson county, Ohio, this 2nd day of May, 1918.

JOHN BEISWANGER.
